UNITED STATES PATENT OFFICE.

GEORGE F. STEEDMAN, OF ST. LOUIS, MISSOURI.

COMPRESSOR.

1,159,123.

Specification of Letters Patent.

Patented Nov. 2, 1915.

Application filed May 4, 1914. Serial No. 836,336.

To all whom it may concern:

Be it known that I, GEORGE F. STEEDMAN, a citizen of the United States, residing at St. Louis, Missouri, have invented a certain 5 new and useful Improvement in Compressors; of which the following is a full, clear, and exact description, such as will enable others skilled in the art to which it appertains to make and use the same.

10 This invention relates to compressors of the type described in United States Patent #770,785, granted to E. H. Steedman, September 27, 1904, wherein the cylinder is provided with a water-jacketed head. In compressors of the type described in the patent above mentioned the valve mechanism is mounted on the head of the cylinder in such a manner that it is necessary to remove the head of the cylinder whenever it is desired 20 to inspect the suction valves, or adjust or replace parts of the valves or the valve mechanism. Consequently, it is not possible to inspect the suction valves or remove or make any change in the valve mechanism when the 25 compressor is in operation.

The main object of my present invention is to provide a compressor of the general type referred to, which is so designed that the suction valves can be inspected when the 30 compressor is in operation and both the suction and discharge valves can be replaced easily. To this end I have devised a compressor in which the water-jacketed head of the cylinder is provided with removable 35 closure members for the valve chambers, which closures can be taken off so as to enable the suction valves to be inspected or both valves removed without removing the head of the cylinder.

40 Another object is to provide a compressor in which the head of the cylinder is provided with a removable closure for the suction valve chamber that carries an actuating device which forms part of the mechanism for controlling the movement of the suction valve. And still another object is to provide a compressor in which a valve seat member that is secured to the head of the cylinder carries or supports the means that holds the 45 suction valve seated, the head being provided with a removable closure for the suction valve chamber that can be taken off without disturbing the suction valve or the means that retains said valve on its seat. 50 Other objects and desirable features of my invention will be hereinafter pointed out.

Figure 1 is a top plan view partly in horizontal section of a compressor constructed in accordance with my invention. Fig. 2 is a vertical sectional view taken on the line 2—2 of Fig. 1; and Fig. 3 is a detail sectional view taken on the line 3—3 of Fig. 2.

Referring to the drawings which illustrate the preferred form of my invention, A 65 designates the removable head of one of the cylinders B, which head is provided with a chamber 1, through which water circulates, and also with a suction valve chamber 2 and a discharge valve chamber 3. The suction valve C preferably consists of a thin metallic disk that is normally held pressed against a valve seat member 5 by means of a spring 6. Said valve seat member 5 is screwed into the head A of the cylinder, as shown in Figs. 70 2 and 3, and it supports a stop bolt 7 that is provided at its lower end with a head 8 having a recess which receives the spring 6 that normally holds the suction valve seated, said stop bolt being connected to the valve seat 75 80 in any suitable manner, as, for example, by a screw-threaded portion on the said bolt that is screwed into the center hub of the valve member 5, which is of skeleton construction. The stop bolt 7 projects upwardly 85 through the suction valve chamber 2 and acts as a guide for the thimble 9, which cooperates with the lever 10 that forms part of the mechanism for governing the valve, as clearly described in the patent above mentioned, one end of said lever 10 being acted 90 upon by a governor plunger 11 which moves the lever 10 and thimble 9 against the force of the spring 12 that is interposed between the thimble 9 and the center hub of the 95 valve seat member 5, as shown in Fig. 3. The suction valve chamber 2 is provided with a removable closure 13 that can be taken off so as to enable the suction valve to be inspected when the compressor is in operation, or when it is desired to remove said 100 valves. Said closure 13 may be retained in position in various ways, but I prefer to securely clamp said closure in position by means of a nut 14 mounted on the upper 105 end of the bolt 7, which bolt passes through an opening in the closure 13. The closure 13 is preferably provided with a depending lug 15, to which the lever 10 is pivotally connected, and, in order to eliminate the possibility of the lever 10 being arranged in an 110 incorrect position, I have provided the clos-

ure 13 with depending guides 16, as shown in Fig. 3, that coöperate with shoulders 17 formed on the edge portions of the opening with which the closure 13 coöperates. The 5 closure 13 is also preferably provided with a spring-pressed device 18 that normally closes an oil hole formed in the closure 13, thus enabling oil to be introduced into the suction valve chamber without removing the 10 closure 13.

The discharge valve D also preferably consists of a thin metallic disk that is normally held pressed against a valve seat member 19 by means of a spring 20, said valve 5 seat member being screwed into the head of the cylinder and said spring coöperating with an abutting member 21 carried by a removable closure 22 for the discharge valve chamber 3.

20 One desirable feature of a compressor of the construction above described is, that the suction valve can be inspected easily while the compressor is in operation simply by removing the closure 13 for the suction valve 25 chamber. And another desirable feature of such a compressor is, that it is not necessary to remove the head of the cylinder when repairs or replacement of both valves or of the suction valve controlling lever 10 is necessary. 30

Having thus described my invention, what I claim is:

1. In a compressor, the combination of a cylinder provided with a head that has a 35 suction valve chamber, a removable closure for an opening in said chamber through which the suction valve can be inspected or removed, a lever that coöperates with a suction valve governing device that is located at 40 a point removed from the suction valve opening, said lever being carried by said removable closure and arranged inside of said valve chamber, and means for preventing said closure from being arranged in such a 45 position that said lever is incorrectly positioned with respect to said governing device.

2. In a compressor, the combination of a cylinder provided with a head that has a suction valve chamber formed therein, a 50 removable device on the head that normally closes an opening through which the suction valve can be inspected or removed, a valve

seat member connected to the head, a suction valve coöperating with said member, means supported by said member for holding the suction valve seated, and a lever that coöperates with a suction valve governing device arranged some distance away from said suction valve, said lever being pivotally mounted on said closure and extending 60 transversely of the valve.

3. In a compressor, the combination of a cylinder provided with a head that has a suction valve chamber, a valve seat member that can be inserted or removed without removing the head, a suction valve, a suction valve spring for keeping the valve normally seated, a stop member integrally attached to said valve seat member and provided with an annular recess for receiving said spring, 70 an easily removable closure member covering the suction valve chamber, a governing device coöperating with the suction valve and located some distance away therefrom, and a lever that forms the connection between 75 said suction valve and said governing device, said lever being pivotally mounted on said closure member and lying within said valve chamber.

4. In a compressor, the combination of a cylinder provided with a head that has a suction valve chamber, a suction valve seat that can be inserted and removed without removing the head, a disk suction valve, a suction valve spring, a stop bolt attached to 85 said valve seat and removable therewith, provided with a recess in its head to receive the suction valve spring, a thimble member sliding on said stop bolt stem above the valve seat and arranged to coöperate with 90 the governing mechanism to hold the suction valve from its seat, a spring around said stop bolt stem to hold the thimble member normally away from the suction valve, a governing means arranged inside of said 95 valve chamber, and a readily removable closure for the suction valve chamber.

In testimony whereof I hereunto affix my signature in the presence of two witnesses, this first day of May 1914.

GEORGE F. STEEDMAN.
